FIG. 5.

FIG. 6.

FIG. 7.

Inventor
Davis Marinsky
By his Attorneys
Edgar Dale & Co.

UNITED STATES PATENT OFFICE.

DAVIS MARINSKY, OF NEW YORK, N. Y., ASSIGNOR TO DAVID HOROWITZ, OF BROOKLYN, NEW YORK.

HAIR-CURLING DEVICE.

1,390,803.

Specification of Letters Patent. Patented Sept. 13, 1921.

Application filed March 18, 1921. Serial No. 453,419.

To all whom it may concern:

Be it known that I, DAVIS MARINSKY, a citizen of the United States, and residing at New York, in the county of Bronx and State of New York, have invented certain new and useful Improvements in Hair-Curling Devices, of which the following is a specification, such as will enable those skilled in the art to which it appertains to make and use the same.

This invention relates to devices used by ladies in curling their hair, and the object thereof is to provide an improved device of this class which is simple in construction and effective in operation, and which may be used with equal facility at either side of the head and by means of which the hair may be easily curled without the use of heat, and with this and other objects in view the invention consists in a device of the class specified, constructed as hereinafter described and claimed.

The invention described and claimed herein is an improvement on that described and claimed in a prior U. S. Patent No. 983,074 granted to me January 31, 1911, and the invention is fully disclosed in the following specification, of which the accompanying drawing forms a part, in which the separate parts of my improvement are designated by suitable reference characters in each of the views, and in which:

Figure 1 is a side edge view of a hair curling device involving my invention;

Fig. 2 a front view thereof;

Fig. 3 a section on the line 3—3 of Fig. 2 on an enlarged scale and with part of the construction broken away;

Fig. 4 a section on the line 4—4 of Fig. 3;

Fig. 5 a back view of a modified form of hair curling device;

Fig. 6 a section on the line 6—6 of Fig. 5 on an enlarged scale and with part of the construction broken away; and,

Fig. 7 a section on the line 7—7 of Fig. 6.

In the practice of my invention, as shown in Figs. 1 to 4 inclusive, I provide a hair curling device *a* comprising two flexible strips *b* and *c* composed of any suitable flexible material, metal, rubber or the like, and

for the purpose of this description, the strip *b* will be called the back strip and the strip *c* the front strip.

The strips *b* and *c* are preferably approximately about the same width as shown in the drawing, except that one end of the front strip *c* is slightly tapered as shown in Fig. 2. The back strip *b* is provided at each end with a head member *b*² having a central aperture *b*³, and mounted on said back strip is a slide member *d* to which the front strip *c* is hinged as shown at *d*². The slide member *d* comprises a yoke-shaped part *d*³ through which the larger end of the strip *c* is passed and folded to form a sleeve *d*⁴ through which is passed a pivot or hinge pin *d*⁵, which is also passed through the side members of the yoke-shaped part *d*³, and this forms a hinge connection for the part *c* with the part *b*, and with this construction the front strip *c* is free to slide on the back strip *b*, and when the slide member *d* is at either end of the back strip *b* the end *c*² of the front strip *c* may be passed through the aperture *b*³ in the other end of said back strip as will be readily understood.

With this form of construction the free end of the front strip *c* may be detached from the back strip and the hair may be wound on either of said strips, but preferably on the back strip, and after this operation is completed the free end portion of the front strip *c* is passed through one of the apertures *b*³, according to the position of the slide member *d*, and this will securely bind and hold the hair in the position in which it is wound and the result of the operation of this device will be similar to that of others of its class though more effectual and lasting in its results.

It will also be seen from the accompanying drawing and the foregoing description that there is a free space *e* between the hinged end of the front strip *c* and the back strip *b* at the point where the strip *c* is connected with the slide member *d*, and this in connection with the form of the slide member *d* and the hinge of the strip *c*, permits the hair to be wound on the strip *b* for almost its full length and close up to the

slide member and prevents the hair from adhering to any of the parts of the device at this point, and leaves it free to slide on the strip on which it is wound in the operation of detaching the device from the hair.

In the construction shown in Figs. 5 to 7 inclusive, I provide a back strip *f* of any suitable material and a flexible front strip *g*, and the back strip *f* is provided with a central longitudinal slot *f*³, and mounted on said back strip is a slide member *h* which is yoke-shaped in form and composed of parallel side parts or ears *h*² and a back portion *h*³, the side edges of which are provided with inwardly turned lugs or projections *h*⁴ which fit in and are movable in the slot *f*³ of the part *f*, and the lugs or projections *h*⁴ are designed to prevent the removal of the slide when in use from the part *f* and the operation thereof to accomplish this result is clearly shown in Fig. 6.

The end *g*² of the strip *g* is tapered so that it may be passed through the slot *f*³ and the other end thereof is hinged between the ears or side members *h*² and the slide *h*, as clearly shown at *i*, said end of said strip *g* being formed into a sleeve *i*² through which a hinge pin or pintle *i*³ is passed.

The form of the slide *h* and method of connecting the strip *g* therewith forms a free space *j* between the part *f* and the part *g*, except where the tapered end *g*² of the part *g* is passed through the slot *f*³, and this permits of the hair being wound close up to the slide on the part *f* in the use or operation of the device and the hair will not be entangled with said part in the operation of winding the hair on the part *f*.

The ends of the back strip *f* instead of being provided with circular heads as shown in Figs. 1 and 2, are preferably tapered as shown at *f*⁴, and this permits the hair to be easily slipped off or removed therefrom after being wound on the part *f* in the operation of using the device for curling the hair.

The method of using this form of construction will be the same as that employed in using the device shown in Figs. 1 to 4 inclusive, except that the hair will probably be wound on the part *f* only and the tapered end of the strip *g* when the hair is fully wound on the part *f* will pass through the slot *f*³ as shown in Fig. 3 and securely hold the hair as long as desired on the strip or part *f*.

It will be observed that as with the construction shown in Figs. 5 to 7 inclusive, the slide *d* cannot be detached from the back strip *b* in the construction shown in Figs. 1 to 4 inclusive, said detachment being prevented by the heads *b*² at the ends of the strips *b*, and it will also be seen with the construction shown in Figs. 5 to 7 inclusive as in the construction shown in Figs. 1 to 4 inclusive, the slide cannot be detached from

the part on which it is mounted, the slot *f*³ being closed at both ends, and in this form of construction the slide *h* may be used at either end of the part on which it is mounted, and the free end of the strip *g* may be engaged with either end of said part, and this facilitates the use of the device as will be readily understood.

Having fully described my invention, what I claim as new and desire to secure by Letters Patent, is:—

1. A hair curling device comprising a main or back member, a slide mounted thereon and adapted to move from one end to the other thereof, and a supplemental or front member hinged at one end to said slide, and means whereby the free end portion of the supplemental or front member may be engaged with either end portion of the main or back member when the slide is at the opposite end portion thereof.

2. A hair curling device comprising a main or back member, a slide mounted thereon and adapted to move from one end to the other thereof, a supplemental or front member composed of flexible material and hinged at one end to said slide, and means whereby the free end portion of the supplemental or front member may be engaged with either end portion of the main or back member when the slide is at the opposite end portion thereof.

3. A hair curling device of the class described comprising two strips one of which is composed of elastic material, a slide mounted on one of said strips and adapted to move from one end portion to the other thereof and to which the flexible strip is hinged, said strips being provided with means whereby the free end portion of the hinged strip may be engaged with either end portion of the other strip when the slide mounted thereon is adjacent to or at the other end portion thereof.

4. A hair curling device of the class described comprising two strips of suitable material, one of which is flexible, a slide mounted on one of said strips and movable longitudinally thereof and to which one end of the other strip is hinged, the strip on which the slide is mounted, and said slide being provided with means at the end portions of said strip to limit the longitudinal movement of the slide, and said strips being provided with means whereby they may be engaged and disengaged at one end of the device when the slide is at or adjacent to the other end thereof.

5. A hair curling device of the class described comprising two strips of suitable material, a slide mounted on one of said strips and movable longitudinally thereof and to which one end of the other strip is hinged, the strip on which the slide is mounted, and said slide being provided with means at the

end portions of said strip to limit the longitudinal movement of the slide, and said strips being provided with means whereby they may be engaged and disengaged at one 5 end of the device when the slide is at or adjacent to the other end thereof.

In testimony that I claim the foregoing as

my invention I have signed my name in presence of the subscribing witnesses this 15th day of March, 1921.

DAVIS MARINSKY.
